MECHANICAL RELEASE DEVICE.

1,182,464.

Specification of Letters Patent.

Patented May 9, 1916.

Application filed February 5, 1916. Serial No. 76,496.

To all whom it may concern:

Be it known that I, JAMES HERBERT EMERY, a citizen of the United States, residing at Morsemere, in the county of Bergen and 5 State of New Jersey, have invented certain new and useful Improvements in Mechanical Release Devices, of which the following is a specification, reference being had therein to the accompanying drawing.

10 My invention refers to an automatic mechanical release device which is adapted to hold certain mechanical parts in a fixed position until a certain pressure is applied thereto or a certain weight thereon increases 15 to a degree where a releasing effect is essential, and then to automatically effectuate the release so that the parts of any particular mechanism with which the device is used may instantly assume a different relation 20 to each other for the performance of the necessary functions of said mechanism.

The object of the invention therefore is to provide a simple, efficient, and mechanical automatic release; and it also relates to various details and peculiarities in the construction, arrangement and combination of the various parts, substantially as will be hereinafter described and then more particularly pointed out in the claims.

30 In the accompanying drawing illustrating my invention: Figure 1 is a side elevation in partial section of my improved automatic release device. Fig. 2 is a top plan view of the same. Fig. 3 is a perspective view of the device applied for use in connection with a steam boiler. Fig. 4 is a view showing a modified form of the device which adapts it for use with a water flushing tank having therein a float valve.

40 Similar characters of reference designate corresponding parts throughout the different figures of the drawing.

1 denotes a main frame of any desired pattern or shape, and designed for attachment in any manner at a point where the device is needed to perform its functions. In one end of this frame is pivoted by means of the pivot 2 a lever 3, preferably of bifurcated form and carrying at its opposite end 50 some suitable ball or counterbalance 4. The same pivot 2 serves as a fulcrum for a horizontal lever 5 situated alongside of the lever 3 and between the parallel bifurcated sides thereof, all as clearly shown in Figs. 1

and 2. One end of the lever 5 projects beyond the lever 3 and is adapted to receive the weight or pressure of a contacting device, such as a pin or arm, an example of which is indicated at 6, while the opposite end of the lever 5 has a lip 7 that engages the inclined face 8 of a trip lever 9 pivoted at 10 to the lever 3, and having at its lower end a catch 11 that engages a spring finger 12 which is secured in some suitable way to the frame 1, said spring finger at its upper end being preferably provided with a small antifriction roller 13 which falls into the notch in the catch 11, the roller permitting the catch to engage and disengage freely. Furthermore, the trip lever 9 is provided with an upwardly-projecting arm 14, through which passes a screw rod 15 having thereon a set-screw 16 and being provided with a spring 17 which connects with an eye 18 fastened to the lever 5. The tension of the spring 17 can, therefore, be easily adjusted by the set-screw 16. The effect of the spring 17 is to draw the trip lever 9 toward the lever 5 so that the face 8 will be over the lip 7 with more or less tension and consequently will regulate the pressure which the free end of the lever 5 is required to overcome in order that it may be depressed sufficiently to cause the lip 7 to lift the inclined face 8 and oscillate the trip lever 9 sufficiently to disengage the catch 11 from the spring detent 12, the occurrence of which disengagement will obviously allow a further pressure on the end of the lever 5 to depress said lever still farther, and lift the lever 3 and trip 9, as also catch 11. The parts are restored to the position where the catch 11 again engages the finger 12 by the weight of the ball or counterbalance 4 at the end of the bifurcated lever 3 when the depressing action on the outer end of lever 5 ceases to act.

Assuming that the parts are in the position shown in Figs. 1 and 2 and that a weight, as for instance the weight 6 in Fig. 1 or some other example of pressure means is resting on the end of the lever 5, it will be understood that so long as the weight 6 remains the same, the parts of the release device will not change their position, but if there is superadded to this device other weights or pressures increasing the ponderability of the same, such increase of pres-

sure will depress lever 5 and when the movement of lever 5 reaches a point where the tension of the spring is overcome by the action of the lip 7 riding on the inclined face 8, the trip lever 9 will be turned on its pivot 10 and will pull out the spring 17 so that the catch 11 will be disengaged and the lever 5 will thus be overcome by the pressures represented at 6 so that the device 10 6 will be set free. The catch 11 is preferably formed with a rounded end 19 which will easily ride over the roller 13, when the pressure of the part 6 has been relaxed, so that the catch 11 may be thrust under the 15 roller 13 by the reaction of the spring 17.

It will be obvious that a device of this kind may serve for many different kinds of mechanism, and I do not wish to be restricted to any particular one. In order that 20 the same may be more thoroughly understood and its principles more fully appreciated, I have shown in Fig. 3 how the device may be applied to a steam boiler, and in Fig. 4 I have indicated a modification 25 in the construction of the device which adapts the same for controlling the closing of the float valve in the flush tank of a water closet or other closet combination. It may be said however that these are only two of 30 many examples which are selected as being helpful in the explanation of a wide variety of uses to which the automatic release may be applied.

Referring now to the case of the steam 35 boiler as shown in Fig. 3, I will explain the same. At the top of the steam boiler 20 is the usual lever 21 pivoted in the support 22 and embraced by the fork 23 which is actuated by the steam pressure in the 40 member 24. On one end of the lever 21 is a counterbalance 25, while at the other end is attached a chain 26 which extends downwardly to the draft door at the bottom of the furnace. When the steam pressure at 24 rises 45 it will lift the weight 25 and will correspondingly lower the chain 6 and close the draft door. The weight 25 can be adjusted on the lever 21 so as to vary the amount of pressure required to lift said weight, and 50 consequently close the draft. When the steam pressure reduces, obviously the draft door automatically opens and the fire is given a chance to speed up again. In applying my invention to a device of this kind, 55 I arrange the lever 5 so that it will occupy the normal position shown in Fig. 1 where the catch 11 is engaged with the detent 12 at a time when the pressure of the steam has risen to a predetermined degree as regulated 60 by the position of the weight 25 and where it is desired to hold the pressure, at which time the lever 21 rests on the lever 5. Since the steam pressure has risen sufficiently to 65 loosen the chain 26, the draft door will be closed and the steam pressure will be suffi-

cient to keep the lever 21 for the time being resting upon the lever 5 of the releasing device. Obviously while the draft door remains closed, the lever 21 will rest with an increasing pressure on the lever 5 as the 70 uplifting pressure of the steam on the lever 21 decreases. It is found, however, in practice that in a steam heating system the steam will remain in the radiators with considerable pressure and giving forth a large 75 amount of heat for a considerable time after the draft has been closed, and consequently the lever 5 will continue in its normal position as shown in Fig. 3 for some little time, that is to say the decrease in the pressure of 80 the steam would not be sufficient until some time has elapsed to force down the lever 5 far enough to disengage the catch 11; although if the lever 5 were not there the lever 21 might be caused to drop by the weight 85 25 so that the draft door would begin to open immediately upon the slightest decrease of pressure, but with my improved device though the steam pressure reduces yet it is not until the pipes have cooled a 90 good deal that the weight of the lever 21 and the counterbalance 25 will be enough to depress the lever 5, disengage the catch 11, lift lever 3 and trip 9 and consequently 95 allow the lever 21 to fall back to a point where the chain 26 will open the draft door and vigorously renew the draft so that the fuel will be again rekindled and combustion greatly increased. Consequently by these 100 means of checking the otherwise automatic action of the steam for a short period, I am enabled to effect a considerable saving in the fuel used.

Referring now to Fig. 4 I have there 105 shown a modification of the invention for effecting a release of the buoyant float belonging to a float valve in a flush tank. The weight 4 used with the arm 3 in the form of the invention shown in Figs. 1 and 2 is omitted, and the arm 3 is changed in form, 110 being lever 40 pivoted at 41, while the lever 5 is transmuted into the form of a lever 27 having a rearwardly extending arm 28 which passes beyond the trip lever 9 for some distance and accordingly performs the same 115 function as the weight 4. The frame 1 is substantially the same as in Fig. 1 and is secured to some convenient wall, frame, or support. In levers 40 at 10 is pivoted the trip lever 9 having the catch 11 which engages the spring finger 12 the same as in Fig. 1. Further, the lever 27 has a lip 7^a which engages the inclined face 8 of the trip lever 9. Adjustably connected to the outer end of the arm 28 of lever 27 by means of a set screw 125 29 or other equivalent device is a slotted link 30, forked or otherwise shaped at 31, to engage the rod 32 of an automatic valve 33 having a discharge nozzle 34 and located 130 conveniently with the flush tank 36 of a

water closet or other water receiving compartment where it is desired to operate such a valve by means of a float 35 lying in the water and buoyant therein. This float is 5 shown at 35 consisting of a buoyant ball which is attached rigidly to the end of the rod 32. Obviously the connection of the rod 32 with the end 31 of the link 30 enables the link 30 when a sufficient pressure is imparted 10 thereto, to lift the lip 7^a and trip the lever 9 so as to disengage the catch 11, then lift trip 9, the effect of which will be to allow the valve 33 to be closed by the action of the float 35. The parts are so arranged and related 15 that the valve 33 will discharge water into the tank 36 and cause a buoyant effect upon the float 35 until such buoyancy attains a degree where it will act upon the link 30 and disengage the trip lever 9 from detent 12 20 when it will rise instantly and close the valve so that there may be no further discharge of water until the valve is again opened. The opening will occur obviously as soon as the contents of the tank 36 are discharged, which 25 will allow the ball 35 to quickly drop and allow the levers 27 and 28 to drop likewise. There is, therefore, a distinct advantage gained in enabling the tank to fill more quickly and at any desired height since the 30 valve will remain wide open until the tank is full and then will quickly close, and there will not be the same slow closing and consequently decrease in the filling action until the tank is full, which occurs with the present 35 arrangement where the float 35 rises slowly on the rising water level and thereby acts gradually on the valve 33. I, therefore, save much water. The operating water level can be made much lower than usual and still have 40 the rod 32 kept straight. There are numerous other incidental advantages which will be readily seen. With this construction of modified form of release device, I employ a similar spring device for tensioning the 45 trip lever 9, though the parts are reversed to correspond to the shape and relation of the mechanical features, such spring part in this case consisting of a spring 37 which is fastened to the upper arm 14 of the trip lever 50 and is attached to a rod 38 which passes through the bent end of the lever 27 and is provided on its screw-threaded section with an adjusting nut 39.

Various other modifications may be devised without exceeding the scope of the invention; also it will be evident that numerous changes in the details of the various parts and their operative relation and mechanical combination may be made without going outside of the legitimate sphere of the invention, and I, therefore, reserve the liberty of so doing as experience may find to be desirable.

It will be obvious that the spring 17 may have substituted therefor a mechanical equivalent in the form of a weight which can be

arranged upon an extension of the trip lever, as for example as shown in dotted lines in Fig. 1, the arm 9 is extended in the form of the arm 42 carrying an adjustable weight 43. This weight being beyond the center 10 of 70 the pivotal point of the trip lever and being adjustable may be a fair substitute for the spring-tensioning means.

Having thus described my invention, what I claim as new and desire to secure by Letters Patent, is:

1. In a releasing device, the combination of a pivoted lever, a second lever supported on the fulcrum of the first, a trip lever pivoted to the first lever and engaged loosely 80 at the end of the second lever, and a tension device between the trip lever and said second lever.

2. In a releasing device, the combination of a pivoted lever, a second lever pivoted to 85 the first, a trip lever pivoted to the first lever and engaged by the end of the second lever, and an adjustable tension device between the trip lever and said second lever.

3. In a releasing device, the combination 90 of a pivoted member carrying a counter-weight, a lever pivoted on the fulcrum of said member, a trip lever pivoted to said member and engaged loosely by the end of said lever, a tension device between the trip 95 lever and the aforesaid lever, together with a detent normally engaged by the trip lever.

4. In a releasing device, the combination of a pivoted lever, a second lever supported on the pivot of the first and having a lip at 100 one end, a trip lever pivoted to the first lever and having an inclined face engaged by the lip of the second lever and having also a catch and an upwardly extending arm, a tension device between said latter 105 arm and the aforesaid second lever, and a detent normally engaged by the trip lever.

5. In an automatic release device, the combination with a main lever having a lip at 110 one end, means for pivotally supporting said lever, a trip lever, means for pivotally supporting it, a tension device attached to the trip lever and the main lever.

6. In an automatic release device, the combination with a main lever having a 115 lip at one end, means for pivotally supporting said lever, a trip lever, means for pivotally supporting it, a tension device attached to the trip lever and the main lever, and a detent which is normally engaged by 120 the trip lever.

7. In an automatic releasing device, the combination with a main lever, means for pivotally supporting the same, a trip lever having an inclined face engaged by the end 125 of the main lever and having also a catch, tensioning means between the trip lever and the main lever, counterbalancing means for the main lever, and a detent normally engaged by the catch.

8. In an automatic releasing device, the combination with a main lever having a lip at one end, a supporting lever in which the main lever is pivoted, said supporting lever being likewise pivotally carried by the same means, a trip lever pivoted in the supporting lever and having a flat inclined face on which the lip of the main lever rides, said trip lever having also a catch, and a tension device consisting of a spring and a rod provided with an adjusting screw, the same being arranged between the trip lever and the main lever for regulating the pressure at which the main lever operates, and counterbalancing means on the supporting lever.

9. The combination with a pivoted main lever, of a loosely supported trip lever having a flat inclined face engaged by the end of the main lever and tripped by the movement of said lever, said trip lever having a catch, a spring device between the trip le-

ver and the main lever, and a detent for normally restraining the trip lever.

10. In a releasing device, the combination of a pivoted member, a lever pivoted on the fulcrum of said member, a trip lever pivoted to said member and engaged loosely by the end of said lever, and means for obtaining an adjustable tension between the trip lever and the other lever, together with a detent normally engaged by the trip lever.

11. In an automatic releasing device, the combination with a main lever, means for pivotally supporting said lever, a trip lever pivoted in the main lever, said trip lever being provided with means for regulating the pressure required to trip it, and a detent which is normally engaged by the trip lever.

In testimony whereof I affix my signature.

JAMES HERBERT EMERY.
